UNITED STATES PATENT OFFICE

JAMES L. BALTON, OF BALTIMORE, MARYLAND

DESIGN FOR AN ICE-CREAM CONTAINER

Application filed October 27, 1930. Serial No. 37,402. Term of patent 14 years.

To all whom it may concern:

Be it known that I, JAMES L. BALTON, a citizen of the United States of America, residing at the city of Baltimore and State of Maryland, have invented a new, original, and ornamental Design for Ice-Cream Container, of which the following is a specification, reference being had to the accompanying drawing, forming part thereof.

In the drawing, The figure is a side view of an ice cream container, showing my new design. The ornamentation on the opposite side of the figure is identical with that disclosed.

I claim:

The ornamental design for an ice-cream container, as shown and described.

JAMES L. BALTON.
